UNITED STATES PATENT OFFICE

GEORGE H. REVELLE, OF SEATTLE, WASHINGTON

MEMORANDUM-PAD HOLDER FOR WALL TELEPHONES

Application filed February 1, 1928. Serial No. 251,067.

This invention relates to a memorandum-pad holder for a wall telephone instrument, the general type shown and described in a patent application, Ser. No. 247,532, filed by me January 18, 1928, with reference to an automatic desk-telephone.

Two main difficulties had with wall telephone instruments of the automatic call-completing type to provide an attachment 10 for holding memorandum-pads thereto are (1) because of the lack of available space upon the instrument to accommodate the holder, and (2) because of the lack of facilities on the instrument itself to which the 15 holder may be readily and firmly secured.

The object of the present invention is to provide a memorandum-pad holder suitable for attachment to a wall telephone instrument, which will be of strong and durable 20 construction, inexpensive to manufacture and convenient for use.

The invention is illustrated in the accompanying drawing, wherein,—

Figure 1 is a front elevation of a wall-telephone instrument with an embodiment of my 25 invention applied thereto; Fig. 2 is a side elevational view of the same; Fig. 3 is a front elevational view of the pad holder shown detached; Fig. 4 is a vertical section taken 30 substantially on the line 4—4 of Fig. 3 and indicating by dotted lines associated parts of the telephone instrument; and Fig. 5 is a horizontal section on broken lines 5—5 of Fig. 3.

Referring to said drawing, the reference 35 numeral 10 designates, as a whole, the framework of a wall-telephone instrument of the automatic type having a wall-board member 11 and a box member 12 protruding forwardly therefrom. 13 represents the mouth-piece, 14 is the receiver, 15 is the cylindrical casing rigid with said box member and containing operating mechanism which is regulated, as usual, by means of a rotary dial 16.

The telephone instrument and devices 45 thereof above referred to are similar to construction now in use. In practice, the mouthpiece 13 and the casing 15 which carries the dial 16 are disposed one below the other on the box member of the frame, sub-

stantially as shown in Figs. 1 and 2 affording but little unoccupied space to accommodate a pad-holder upon the front of the box member.

The dial 16 is provided with a plurality of 55 circumferentially disposed finger receiving apertures 17 which may be used selectively to rotate the dial with respect to a finger engaging stop 18 having a shank element 19 secured to the periphery of the casing 15. 60

According to the present invention I provide for the above described instrument a holder for a book 20 of removable sheets of paper having a backing of cardboard, or the like, and conventionally known as a "scratch 65 pad" or "pad," as hereinafter designated.

The holder, above referred to, comprises a sheet metal plate 21 of a general rectangular shape, see Fig. 3, of a size to receive thereon the pad 21, the card-board backing 70 thereof engaging against the plate. Said pad is retained upon the plate against relative displacement in the plane of the plate between lug elements 22 and 23 projecting forwardly from the upper side edges, respectively, of the plate, and also between lug elements 24 and 25 projecting forwardly from the plate's top and bottom edges respectively. Said lugs are desirably formed by providing the plate with protruding portions and bending the same forwardly to constitute the respective stops. To retain the pad 20 against said plate the lug 24 is provided with a spur 26 adapted to penetrate 75 the upper portion of the pad; and by forming the lug 25 to the shape of hook, see Fig. 4, into which extends the lower edge of the card backing. 80

Said plate is formed to provide a plane 90 back surface 27 (Fig. 5) at one side of a rib element 28, said back surface 27 fitting against the front surface 12¹ of the instrument box 12 and the rib 28 fitting against the outer portion of the side surface 12² of the box. 95

For thus securing the holder to the box member 12 of the telephone instrument, I provide a fastening means comprising a piece of spring wire formed to a circular shape 100 permanently secured intermediate its length

to one side of the plate member of the holder, the portions 29 and 30 above and below the place of its securement to the plate serving as arms to mutually embrace the casing 15. Said fastener is arranged in the plane of the plate, or nearly so, and is rigidly secured to the latter by welding or by other suitable known means. As illustrated, said wire fastener extends through eyes of rolled projections 31 of the holder plate.

10 Said wire fastener by engaging the casing 15 serves to retain the plate against the front surface of the box 12 and also the rib element against one side edge of the box whereby the holder is maintained against accidental movement in every direction.

15 To supplement the function of the rib 28, however, a lug element 33 is advantageously provided at one side of the plate to abut 20 against the stop shank 19 provided upon the casing. Said holder is also desirably provided with a pencil attaching means such, for example, as a socket element 34 provided at one side of the plate 21 to receive a pencil 25 which is indicated by 35.

The invention, and its advantages, it is believed, will be understood from the description of the illustrated embodiment thereof.

What I claim is,—

30 1. A memorandum-pad holder for a wall telephone instrument having a box member and a circular casing containing switching mechanism, said holder comprising a plate member adapted to seat in juxtaposed relation to the face portion of the box member, an arm secured to said plate member for embracing engagement to said casing, means to engage a pad to said plate member and depending means integral with said plate member and engageable to a side of said box to retain said plate member against rotative displacement about the casing.

45 2. The combination with a wall telephone instrument having a box member and a circular casing containing switching mechanism, of a holder detachably engageable to said telephone instrument and adapted to contain a memorandum-pad, said holder comprising a plane plate member arranged to seat in juxtaposed engagement to the face of said box member, a depending portion integral with said plate member and engageable to a side of said box member and a resilient arm arranged to be sprung about said circular casing into embracing engagement thereto.

Signed at Seattle, Washington, this 25th day of January, 1928.

GEORGE H. REVELLE.
